(57) **CLAIM**

The ornamental design for a dust collector, as shown and described.

DESCRIPTION

FIG. 1 is a perspective view embodying the inventive dust collector, wherein the dust collector is expanded and ready for use with its backing attached to the adhesive;

FIG. 2 is a front view of the device as seen in FIG. 1; FIG. 3 is a right side view of the device as seen in FIG. 1; FIG. 4 is a rear view of the device as seen in FIG. 1; FIG. 5 is a left side view of the device as seen in FIG. 1; FIG. 6 is a top side view of the device as seen in FIG. 1; FIG. 7 is a bottom side view of the device as seen in FIG. 1;

FIG. 8 is a perspective view embodying the inventive dust collector as seen in FIG. 1, wherein the backing is no longer attached to the adhesive;

FIG. 9 is a front view of the device as seen in FIG. 8; FIG. 10 is a right side view of the device as seen in FIG. 8; FIG. 11 is a rear view of the device as seen in FIG. 8; FIG. 12 is a left side view of the device as seen in FIG. 8; FIG. 13 is a top side view of the device as seen in FIG. 8; FIG. 14 is a bottom side view of the device as seen in FIG. 8;

FIG. 15 is a perspective view embodying the inventive dust collector as seen in FIG. 8, wherein the dust collector is shown in use with exemplary environmental structure; and, FIG. 16 is a perspective view of the device as seen in FIG. 1, wherein the dust collector is collapsed.

The broken line showing is for the purpose of illustrating environmental structure and forms no part of the claimed design.
